REGULATING MEANS FOR A GAS PISTON
OPERATED GUN

Bernard Maillard, Geneva, Switzerland, assignor to Brevets Aéro-Mécaniques S.A., Geneva, Switzerland, a society of Switzerland

Application July 9, 1956, Serial No. 596,674

Claims priority, application Luxembourg July 26, 1955

5 Claims. (Cl. 89—193)

The present invention relates to automatic guns of the gas tap type, that is to say the barrel of which is provided with a gas tap extending between the inside of said barrel and the outside, generally at right angles to the barrel axis, for feeding some amount of powder gases, immediately after the projectile has moved beyond the gas tap, to a device operated by the pressure of said gases and which cooperates in the automatic operation of the gun.

It is well known that with such guns, when a long burst is fired, the gun being initially cold, the rate of fire varies during the burst due to the modifications in the firing conditions caused by the heating of some parts of the gun (which heating causes said parts to expand, modifies the lubricating conditions and so on). This variation of the rate of fire which, in fact, is an increase of said rate, may cause serious damages when a very long burst is fired. As a matter of fact, the parts of the gun are adjusted to give initially, that is to say when the gun is cold and even at low temperatures, the normal rate of fire, and an increase of said rate beyond a given value may have serious consequences on the operation of the gun and in particular of the cartridge feed device thereof.

The object of my invention is to obviate this drawback.

For this purpose, I provide, between the gas tap and the device to be operated by the powder gases under pressure, heat responsive valve means arranged to control the passage through which said gases can flow so as to vary the cross section of said passage in response to variations in the temperature of operation of at least one part of the gun.

A preferred embodiment of the present invention will be hereinafter described with reference to the accompanying drawing given merely by way of example and in which:

Fig. 1 is a vertical sectional view of a portion of an automatic gun made according to my invention.

Fig. 2 is a similar view on an enlarged scale of part of the structure of Fig. 1.

Fig. 3 is a view similar to Fig. 2 showing a modification.

Fig. 4 is an explanatory diagram to be referred to hereinafter.

The automatic gun shown on the drawing includes a barrel 2 provided with a gas tap 1 through which the powder gases are fed to a cylindrical cavity formed in a support 9 and one end of which constitutes a cylindrical chamber 3 in which is slidably a piston 4 which constitutes a power element for controlling for instance the release of the gun breech block (not shown on the drawing).

In order to prevent an undesirable rise of the rate of fire of this gun when a long burst is fired, I provide, in the construction of Figs. 1 and 2, a core 5 housed in a cylindrical portion of said cavity adjoining chamber 3, said core being mounted with a suitable annular clearance

2

between its periphery and the wall of said cylindrical cavity portion, as visible at 6. The gases from tap 1 are conveyed through a conduit 7 to the above mentioned bore upstream of said annular passage 6 so that they 5 must flow through said passage in order to reach chamber 3.

Said core is carried by a plug 8 screwed in the support 9 in which the cavity is formed, conduit 7 being also formed in said support 9. The left hand portion of plug 10 8 may be provided with a blind hole 10 intended to facilitate cooling thereof.

With such an arrangement, core 5 may be considered as a kind of throttle valve member expandable in response to its being heated so as to modify the cross section of 15 passage 6. This result is due to the fact that, plug 8 and support 9 being for instance both made of steel, when a relatively long burst (for instance 100 shots) is fired, core 5 expands more rapidly than the cylindrical wall of the bore in which it is housed in support 9 so that the 20 cross section of annular passage 6 decreases, which tends to reduce the rate of fire. The materials of which support 9 and the core 5 are made may be chosen so that the core expands more rapidly than the support 9.

In actual practice, it may often happen that this cross 25 section reduction is too great and that, despite the tendency of the gun to have its rate of fire increased as a consequence of its being heated up, the rate of fire actually decreases due to too great a reduction of the cross section of passage 6. In order to overcome this 30 drawback, it suffices to provide through core 5 passages 11 through which a portion of the gases flows directly from conduit 7 into chamber 3.

On Fig. 4, I have plotted in abscissas the temperatures 35 and in ordinates the cross sections through which the gases can flow. The lower rectangle corresponds to 40 passages 11 whereas the trapezium above this rectangle corresponds to the variable cross section of annular passage 6. It is thus possible, by suitably choosing the initial cross sections, to obtain the desired relative variation of the total cross section when the arm is heating by firing.

In the modification of Fig. 3, passage 7 opens directly 45 into a cylindrical bore 12 provided in support 9, the end 13 of this bore being of frusto-conical shape and communicating with a passage 14 leading to chamber 3, the whole of bore 12, passage 14 and chamber 3 forming the above mentioned cavity.

A hollow plug 15 having a nut-shaped head 16 is 50 screwed in cylindrical bore 12 and the end 17 of said plug is conical shaped so that when plug 15 has been screwed in position, this point 17 is located opposite the frusto-conical end 13 of bore 12 and leaves, between 13 and 17, an annular passage 18 of suitable cross section.

When a long burst is fired, rod 17 is heated and expands 55 quicker than member 9 so that the cross section of annular passage 18 decreases. The lefthand portion of the rod 17 may be provided with a blind hole 20 in communication with the atmosphere.

The result is the same as with the arrangement of 60 Fig. 2. In this case also, passages 19 of suitable constant cross section may be provided either in the end of rod 17 or in the portion 13 of the support, so as to ensure the desired variation of the rate of fire.

In a general manner, while I have, in the above 65 description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. An automatic gun comprising, in combination, a barrel provided with a gas tap, means carried by said barrel forming a chamber communicating with said gas tap whereby gases flow from said gas tap into said chamber every time a shot is fired, a piston movable in said chamber in response to pressure rises therein, and valve means interposed between said gas tap and said chamber for varying the flow of gases from said gas tap to said chamber, said valve means comprising a plug mounted in said chamber and having a free end of lessened diameter extending toward said piston beyond said gas tap so as to always leave an annular passage between the free end of said plug and the walls of said chamber for the passage of gases from said gas tap to said chamber, said free end being expansible under the effect of heating by the gases flowing from said gas tap to said chamber during a burst of firing of the gun, whereby the cross-section of said annular passage is reduced as the burst becomes longer and longer, said plug being further provided with at least one other passage between said gas tap and said chamber and formed in said free end so that its cross-section is but little varied by thermal expansion of the free end of said plug.

2. An automatic gun according to claim 1 wherein said plug is provided with a blind hole in communication with the atmosphere.

3. An automatic gun which comprises in combination a barrel provided with a gas tap, means carried by said barrel forming a cavity in communication with said gas

tap whereby powder gases flow from said barrel to said cavity every time a shot is fired, one end of said means being in the form of a cylindrical chamber, a power piston slideable in said chamber in response to pressure rises therein, said means being provided with a transverse partition having a central hole extending between said chamber and said cavity, a rod supported by said means at the end of said cavity opposed to that formed by said chamber, said rod extending toward said partition beyond said gas tap to always leave an annular passage between the free end of said rod and the wall of said partition, said free end being expansible under the effect of heating by the gases flowing from said cavity to said chamber during a burst of firing of the gun, whereby the cross-section of said annular passage is reduced as the burst becomes longer and longer.

4. An automatic gun according to claim 3 wherein said rod is provided with a blind hole in communication with the atmosphere.

5. An automatic gun according to claim 3 and further including at least one passage in parallel with said annular passage and formed so that its cross-section is but little varied by thermal expansion.
